United States Patent Office.

ALEXANDER VAN VLECK AND THOMAS PHILLIPS, OF JORDAN, NEW YORK.

Letters Patent No. 105,610, dated July 19, 1870.

IMPROVED MILLSTONE-CURB.

The Schedule referred to in these Letters Patent and making part of the same.

To all whom it may concern:

Be it known that we, ALEXANDER VAN VLECK and THOMAS PHILLIPS, of Jordan, in the county of Onondaga and State of New York, have invented a new and useful Improvement in Millstone-Curbs; and we do hereby declare that the following is a full, clear, and exact description thereof, which will enable those skilled in the art to make and use the same, reference being had to the accompanying drawing forming part of this specification, in which—

Figure 1 is a perspective view of our invention, and Figure 2 is a horizontal section of the same.

Figures 3 and 4 show a modification of the valve.

Similar letters of reference indicate like parts in the several figures.

In millstone-curbs, as ordinarily constructed, the sweat or moisture, caused by the friction or heat of the stone, settles on the inside wall of the curb, and flour-dust becomes fixed in said moisture to such an extent that a thick formation of dough is soon made on said inner surface of the curb, and becomes sour and foul, and the curb has to be cleaned as often as the stone is lifted.

This invention relates to an improved method for obviating this objection; and

The invention consists in making two or more openings in the wall of the curb, so that the air can pass freely through them, and providing, in connection with one of these openings, an adjustable butment valve or door, for creating a circulation of air through the said openings, as hereinafter more fully explained.

In the accompanying drawing—

A is the curb,

H is the stone, and

F is the discharge for the flour.

The curb A is made with three openings, C D E, fig. 2, and the opening C is provided with an adjustable door or valve, B, to regulate and cause the circulation of air through the holes or openings in the sides of curb A. This door is hung on a shaft or pivot, at one edge. The said shaft stands vertically, and its upper end projects upward through the top of the curb or casing, and a set-screw, g, fig. 1, passing through a slotted segment, G, that is fastened to the upper end of the said shaft, serves to set or fasten the valve B in any position desired.

Its operation is as follows:

The revolving stone H causes a rotative movement of air within the curb, in the direction shown by the arrows, fig. 2. The valve B is set partly open, as shown, and the revolving stone draws in a current of air at the opening or port C, and this air passes around inside of the curb until its further passage is obstructed by the valve B, and this causes it to flow out through the opening D, and, by this means, a constant circulation of air through and around, inside of the curb A, is obtained, and this prevents the moisture from settling on the curb, and thereby obviates the formation of paste or dough on the walls of the curb, as heretofore.

The flour-discharge F is placed immediately in the rear of the valve B, so that the obstruction of the air by the said valve, at this point, shall favor the flow or passage of flour-dust into the discharge F.

But two openings, C and D, are necessary for producing the circulation of air, but one or more additional openings, E, can be made.

The valve B can be set at various angles, so as to give a greater or lesser degree of circulation, as desired; and, in cold weather, during the winter, when it is desirable to retain all of the heat within the curb, it can be closed entirely.

The valve B can be made in the form of a sliding door, and operated by set-screws b b, figs. 3 and 4, and can be arranged in various ways so as to form the obstruction or abutment as the door is opened.

By these means, the waste and labor of cleaning the curb, arising from said fouling, is obviated, and the action of the devices for circulating the air can be regulated, or shut off altogether, as desired.

We do not claim, broadly, a millstone-curb, provided with ventilating apertures; but

What we do claim is—

The combination, in the millstone-curb A, of two or more openings C D E, with the adjustable valve B, when constructed and arranged in the manner and for the purpose herein set forth.

The above specification of our invention signed by us this 5th day of April, 1870.

ALEX. VAN VLECK.
THOMAS PHILLIPS.
